THREE-WHEELED TRACTOR

George Siems, Fairmont, Minn. 56031

Filed Nov. 10, 1966, Ser. No. 4,613

Term of patent 14 years

(Cl. D14—3)

FIG 4

FIG 5

FIG 6

FIG. 1 is a perspective view taken from a position at the left and front, looking rearwardly, of a three-wheeled tractor;

FIG. 2 is a right side elevational view of the same;
 FIG. 3 is a left side elevational view of the same;
 FIG. 4 is a top plan view of the same;
 FIG. 5 is a front elevational view of the same; and
 FIG. 6 is a rear elevational view of the same.

I claim:

The ornamental design for a three-wheeled tractor, as shown and described.
